STABILIZED RADIO CIRCUITS

Application filed March 15, 1927. Serial No. 175,500.

This invention relates to radio frequency circuits, and especially to electronic emission amplifier circuits of this type, utilized in connection with telephone or telegraphic signaling.

When electronic emission devices are utilized for radio frequency amplification, certain deleterious effects are noted. This can be more readily explained when the nature and structure of such electronic emission devices are elucidated.

Such devices usually comprise a plurality of electrodes enclosed in an evacuated vessel.

One of the electrodes serves as a source of electronic emission, and is usually in the form of a filament heated by the passage of an electric current therethrough. This filament thus forms a cathode, from which electrons flow in the space of the vessel to the plate electrode, or anode that is kept at a potential positive with respect to the filament, as by a "plate" or "B" battery. The "space current" between the plate and filament thus flows through the external battery circuit.

The function of amplification is rendered possible by the fact that the space current is very sensitive to the electrical conditions in the tube. For example, a control electrode (usually in the form of a grid) can be placed so as to influence the electron emission, and the influence is a function of the potential difference between it and the filament. Thus minute variations in potential difference applied between the grid and filament can cause comparatively large corresponding variations in the plate circuit. All this is now well understood, and is referred to here merely to provide a foundation upon which the description of the present invention is based.

It has been found that when radio frequency currents are passed through such thermionic repeaters or amplifiers, the capacity effect between the electrodes may cause the system to be unstable, especially at the higher frequencies; the instability is manifested by a tendency for the tube or repeater to generate disturbing oscillations. It has been proposed to utilize some form of damping, such as resistances, to prevent these oscillations; and also, to provide so-called neutral-

izing circuits which are intended to compensate for such parasitic coupling. The damping arrangement is obviously impractical because it introduces losses that prevent sharp tuning; and the neutralizing circuits need accurate adjustment.

It is accordingly one of the objects of my invention to provide a stabilizing scheme that overcomes these disadvantages, and to make it possible to construct amplifier systems in a simple manner, that do not require such extreme delicacy in adjustment.

It is another object of my invention to make it possible to feed back energy from the output side to the input side of such an amplifier system, in order to reamplify the currents and their variations, and yet without the danger of the feed-back (or "regeneration" as it is usually called) becoming unstable and causing undesired oscillations.

My invention possesses many other advantages, and has other objects which may be made more easily apparent from a consideration of several embodiments of my invention. For this purpose I have shown a few forms in the drawings accompanying and forming part of the present specification. I shall now proceed to describe these forms in detail, which illustrate the general principles of my invention; but it is to be understood that this detailed description is not to be taken in a limiting sense, since the scope of my invention is best defined by the appended claims.

Referring to the drawings:

Figures 1 to 4 inclusive are wiring diagrams of four embodiments of my invention.

Fig. 5 is a reactance diagram of a parallel resonant circuit, discussed hereinafter.

In Fig. 1 I show one stage only of my amplifier system, but of course it is understood that any desired number can be connected in cascade, so far as practicable. Also, I have indicated my system as applied to the reception of radio signaling energy, but it is not limited to this field. Thus I show a conventional form of pick-up system, comprising antenna 11, loading coil 12, and a ground connection 13. A tunable circuit 14, comprising a coil 15 coupled to coil 12, and a variable condenser 16 paralleling coil 15, receives the

minute signaling energy and causes it to affect a thermionic amplifier tube 17. For this purpose, one terminal of condenser 16 is connected to control electrode 18, and the other terminal to filament 19. This filament is arranged to be heated by electrical energy, as from a battery 20. The negative side of the filament 19 can be grounded, as indicated at 21.

10 The electrons from filament 19 flow to the anode or plate 22, which is joined to the filament 19 externally of the tube 17 through the following "output circuit"; coil 23, coil 24, positive terminal of B battery 25, battery 25, filament 19. A by-pass condenser 26 can be shunted around battery 25 to permit the radio frequency component of the output current to pass around the battery 25. The signaling impulses cause correspondingly 15 large impulses of current in this output circuit, which can be coupled to a succeeding stage in a well-understood manner to provide another stage of amplification. This is indicated by the placing of a tunable circuit 20 in inductive coupled relation with coil 23; this circuit can affect a succeeding tube, such as 17 already described, in a manner similar 25 to that disclosed.

30 As thus far described, the system does not differ materially from what is well-known. The capacity effect between grid 18 and plate 22, together with the inductance of the output circuit, may produce instability by feed-back; and this too, is now well-understood. 35 In order to keep the system stable, I propose to prevent undue feed-back by making that portion of the output circuit which is coupled to the input, have a capacitive reactance for the range of operation of the system. In 40 this way, the phase relations between the currents in the input and output circuits are made such that the capacitive coupling between grid 18 and anode 22, tends to stabilize the system by causing negative rather than 45 positive feed-back. In order that the resultant negative feed-back may not result in a loss of amplification, and also in order that reactive coupling between circuit 14 and circuit 27 may be reduced substantially to zero, thereby making the tuning of each independent 50 of reactive effects due to tuning of the other, I provide means for balancing the system.

55 To secure this result, the high frequency component of the output current is caused to traverse a network of inductances and capacities; for instance, a coil 28, similar to coil 23, is in parallel therewith as regards inductance 24; and is in inductive relation with coil 23, although not necessarily closely coupled therewith. Furthermore, equal condensers 29 and 30 are placed in parallel relation with inductance 24, by being connected to that terminal of inductance 24 which is 60 nearest the battery 25; the other terminals

of condensers 29 and 30 being connected to the ends of coils 28 and 23 respectively. A condenser 31, of the value of the parasitic capacity of the tube electrodes, joins grid 18 to one side of the network 24—23—28—29—30, as indicated.

Whatever electromotive force is induced in circuit 27 via coil 23 due to the capacity effect between grid 18 and plate 22 is neutralized by the substantially equal and opposite electromotive force induced therein by coil 28, which is symmetrically arranged with coil 23 with respect to the coil of circuit 27. A symmetrical system is thus brought about by the fact that the condensers 29 and 30 have equal values, coils 23 and 28 have the same self inductances, and the same mutual inductance with the coil of circuit 27, and capacity 31 has the same value as the capacity between grid 18 and plate 22. The effects of other parasitic coupling between the input and the output circuits may be reduced substantially to zero by properly arranging the battery wires and by providing suitable shielding between the circuits, indicated 35 diagrammatically by numeral 32, all in the manner well understood by those versed in the art.

Now considering the output circuit for the first stage, it is seen that coil 24 is in series therewith; and paralleling this coil are the two branches 28—29 and 23—30. By proper choice of the constants of coil 24 and the equal condensers 29 and 30, it is easy to ensure that it and its paralleling branches will have a maximum impedance (which is the condition of parallel resonance) for a frequency considerably below the lower limit of the range of operation of the system. For example, for the usual broadcast range, which now extends from 550 to 1500 kilocycles, the frequency of parallel resonance of this circuit can advantageously be about 400 kilocycles, giving a reactance curve of the type shown in Fig. 5. This curve has two branches, marked α ; but due to the range of operation as indicated, only a portion of the right hand branch is used. This portion indicates a negative reactance. Since the effect of including such a circuit in the output side of the tube is the same as introducing a capacitive reactance therein, there is no tendency to produce oscillations, and the system is stable. Furthermore, circuit 27, having equal effect on coils 23 and 28, which in turn are connected to a system of fully balanced capacities, cannot react on the preceding stage through the capacity coupling in tube 17.

It is possible with this scheme to obtain some regeneration without danger of losing stability, simply by coupling coil 24 to coil 15. It is found that if that be done, the regeneration increases as the frequency decreases, since the coil 24 has its impedance reduced with the frequency. This is desir-

able in ensuring a substantially uniform degree of amplification for the whole range of frequencies.

Another form of my invention is shown in Fig. 2. This form operates substantially like that of Fig. 1, and differs therefrom only in a few details. For example, coil 23 is closely coupled to a coil 33 in a tunable circuit 34, which coil 33 is in series with the condenser branch of the tuned circuit. Furthermore, the common terminal of condensers 29 and 30 is directly connected to ground, and is not directly connected to one terminal of coil 24. In both forms of Figs. 1 and 2, the series circuit consisting of the two branches 23-28 and 29-30 is also designed to be resonant to a frequency below the range of operation of the system, whereby the reaction on the succeeding stage is also capacitive. Thus the coupling of this circuit to the capacity branch of circuit 34 in Fig. 2 has the effect of adding a capacity in series to the variable condenser 35 already present in the branch.

Substantially the same effects as in the two forms discussed can be obtained in the form shown in Fig. 3. In this figure, the antenna circuit 11-12-13 is arranged to affect a tunable circuit consisting of coils 36 and 37, both coupled to coil 12, fixed condensers 43 and 44, and variable condenser 38. The thermionic amplifier 39 has the three usual elements 40, 41 and 42. Its control electrode 41 connects directly to one terminal of condenser 38, while filament 40 connects to the common terminal of the pair of equal condensers 43 and 44 that are arranged in shunt to condenser 38. The filament also connects, by way of grounds 50 and 51, with the common terminal of coils 36 and 37, which are wound in the same direction. The output circuit is conventional, and includes primary 45 of a radio frequency transformer, the secondary 46 of which forms one element of a tunable circuit 47 for affecting the succeeding stage. A neutralizing circuit extends from the plate to the lower terminal of coil 37, and includes a capacity 48 which is equal to the capacity between grid 41 and plate 42. A shield 49 serves to isolate the two stages from each other so far as undesired couplings are concerned.

It is well understood that whatever effect the inter-electrode capacity has to induce an electromotive force across coil 36 is counterbalanced by the electromotive force induced in coil 37 due to the neutralizing circuit from plate 42 to coil 37. In accordance with my invention, I stabilize this arrangement for the range of operating frequencies by including an inductance coil 52 in the connection from filament 40 to coils 36 and 37. A "C" battery 53 can also be provided in this connection if desired. There is thus a parallel circuit joined by this coil, which includes in one branch, condenser 43 and coil

36; and in the other, condenser 44 and coil 37. Since this circuit taken with the condenser 48 and the coupling between grid 41 and plate 42, is symmetrical, it is readily seen that there is no reactive coupling between circuit 47 and the input circuit which includes coils 36 and 37. Furthermore, coil 52 is made of such value that the parallel circuit comprising coil 52 and branches 36, 43 and 37, 44 which parallel it, has a natural period 75 below the range of operation of the system. As in the other forms, this has the effect of stabilizing the operation of the system within that range.

In Fig. 4 I show a circuit that is similar in most respects to Figs. 1 and 2; it is designed however, primarily to ensure a substantially equal amplification for all signals within the tuning range of circuits 14 and 27. The manner in which this is accomplished will now be described. The input circuit of tube 17 is the same as in Figs. 1 and 2. The output circuit includes a coil 54 (that is closely coupled to another equivalent coil 55 in the neutralizing circuit), coils 23 and 24 similar in action to the same numbered coils in Fig. 2, and battery 25. Coils 28 and 23 need not be very closely coupled together. The succeeding stage 27 should be symmetrically coupled to 23 and 28 as in Figure 7 and 95 also symmetrically coupled to coils 54 and 55. This is necessary in order that the potentials induced in these coils by currents in the coil of circuit 27 may be symmetrically distributed in the balance of the system. 100

As in Fig. 2, the network 54-55-23-28-30-29-31 and capacity 18-22 is symmetrical; there is no reactive coupling between circuit 14 and circuit 27. Furthermore, by proper choice of constants, the output circuit can be caused to have a substantially constant effect on the input circuit, whereby uniform amplification is obtained, and without instability. This is rendered possible by the coils 54 and 55, which being 105 in series with the rest of the system, have a rising positive impedance as the frequency increases; and to this is added the falling negative impedance of the parallel system 23-28-29-30; the net result is a substantially constant impedance as well as coupling between the input and the output side, and between the stages. In order to effect this result, the coupling of coils 54 and 55 must be such as to assist the effect of the coupling of coils 23 and 28; and their natural period must also be outside the operating range of the system. 110

It is noted that in all of the modifications, a four arm bridge is provided, in each arm 125 of which there is a capacity; and across the opposite corners the various circuits are connected.

Thus analyzing Fig. 1 in detail, the four arms forming a closed circuit are formed 130

respectively by capacity 31 for the first arm; capacity 29 for the second arm; capacity 30 for the third arm; and the capacity between the plate 22 and grid 18 for the fourth arm. The grid 18 is connected between the first and fourth arms; that is, between capacity 31 and the grid-plate capacity. The filament 19 is connected to a point opposite the grid; that is, between the second and third arms, formed by capacities 29 and 30. The input circuit also connects to these two points.

Now considering the other two corners of the bridge, plate 22 is connected between the third and fourth arm; that is, between capacity 30 and the grid-plate capacity. The coils 28, 23 are connected across the diagonal between the extremities of capacities 29 and 30. Due to the fact that the input circuit is connected across the other diagonal, and that the various capacities forming the bridge are properly proportioned, the input circuit cannot be affected by any potential difference that may occur across coils 23 and 28; and conversely, the input circuit cannot affect these coils through the parasitic grid-plate capacity. Thus the stages of amplification are isolated one from another, and principally by the aid of a capacity bridge.

The analysis of Fig. 2 as regards the bridge circuit is the same as of Fig. 1. The main difference is in the mode of connection of coil 24, but this does not alter the bridge structure detailed in connection with Fig. 1.

In Fig. 3, a similar bridge is formed, but slightly differently arranged. The four arms forming a closed circuit are formed respectively by the grid-plate capacity; the second, by capacity 48; the third, by capacity 44; and the fourth, by capacity 43. The grid 41 connects between the first and fourth arms; that is, between the grid-plate capacity and capacity 43. The filament 40 connects between capacities 44 and 43. Plate 42 connects between the first and second arms; that is, between the grid-plate capacity and capacity 48.

The input circuit 36—37—38 connects across one diagonal of the bridge; that is, one terminal connects between the first and fourth arms; and the other terminal between the second and third. The output coil 45 connects across the other diagonal of the bridge; that is, one terminal connects between second arm 48 and the first arm formed by the grid-plate capacity; and the other terminal connects between the third and fourth arms 44 and 43. As before, due to the proportioning of the capacities in the bridge, the potential differences across the output coil 45 cannot affect the input side; and conversely, the input side cannot affect the output side through the grid-plate capacity.

In Fig. 4, the bridge arms are the same as in Fig. 1, except that in the second and third

arms, formed respectively by the capacities 29, 30, there are respectively included the coupled coils 55 and 54. However, these arms are substantially entirely capacitive, the effect of the impedances of the coils 55, 54, being small. The output circuit including coils 23, 28 are substantially across a diagonal of the bridge as before, by connecting across condensers 29, 30.

I claim:

1. In an amplifying system, an electronic emission device, having a plurality of electrodes, an input circuit for said device, an output circuit for said device, means associated with at least one of said two circuits to oppose the effect of capacitive coupling between the electrodes, and means forming with said associated means, a parallel resonant circuit the resonance period of which is below the range of operation of the system.

2. In an amplifying system, an electronic emission device having a plurality of electrodes, an input circuit connected to the input electrodes, an output circuit connected to the output electrodes, said output circuit including a series inductance, a parallel circuit connected to the inductance and forming therewith a circuit that is resonant at a frequency below the range of operation of the system, and another circuit connecting one of the input electrodes and said parallel resonant circuit and arranged to neutralize the capacity effect between two of the electrodes.

3. In an amplifying system, an electronic emission device, an input circuit for said device including a coil, an output circuit for said device including a coil inductively coupled to the coil in the input circuit, and means whereby the effect due to this coupling, upon the input circuit is that of a capacity reactance within the range of operation of the system.

4. In an amplifying system, an electronic emission device having a plurality of electrodes, an input circuit connected between the input electrodes, a parallel circuit having a capacitive and an inductive section, and resonant at a frequency below the range of operation of the system, an output circuit connected between the output electrodes and including the inductive section, the capacitive branch including a pair of coupled coils one of which is also included in the output circuit, and a circuit extending from the other of said coupled coils to one of the electrodes of the input circuit and including a capacity in series that is equivalent to the capacity between said one of the electrodes and an output electrode.

5. In an amplifying system, an electronic emission device having an electron emitting electrode, a control electrode and an anode, an input circuit connected between the electron emitting electrode and the control electrode, a pair of equal inductance coils cou-

pled together, a pair of equal capacities connected in tandem across both coils in series, a connection between the anode and that terminal of one of the capacities which is directly connected to one of said inductance coils, a capacity between that terminal of the other capacity which is directly connected to the other coil and the control electrode, said capacity being equal to the capacity between the control electrode and the anode, and an inductance coil connected between the two coupled coils and the pair of equal capacities.

6. The combination as set forth in claim 5, in which the last mentioned inductance coil is inductively coupled to the input circuit, and in which the net work comprising the pair of coupled coils, the pair of equal capacities, and the last mentioned inductance coil has a parallel resonance at a frequency below the range of operation of the system.

7. The combination as set forth in claim 2, in which the series inductance is coupled to the input circuit.

25 8. The combination as set forth in claim 2, in which a close inductive coupling is provided between the circuit that connects one of the input electrodes with the parallel circuit, and the output circuit.

20 9. The combination as set forth in claim 4, in which a pair of equal closely coupled inductance coils are provided, one being in series in the circuit that includes the capacity equivalent to the inter-electrode capacity, and the other in series in the output circuit.

10. The combination as set forth in claim 5, in which a pair of equal closely coupled inductance coils are provided, one being in series in the connection between the anode and one of the capacities, and the other in series with the capacity that is equal to the capacity between the control electrode and the anode.

11. An electrical amplifying system having in combination a plurality of electronic amplifiers arranged in cascade, circuits adjustable for resonance over a range of frequencies interconnecting said amplifiers, means for reducing reactive couplings between said resonant circuits to negligible values including a parallel resonant circuit having a frequency below the range of operation of the system, and means whereby the amplification of each of the amplifiers in the system is maintained substantially constant over the range of frequencies covered by the adjustable resonant circuits.

12. In an amplifying system, an electronic emission device having input and output electrodes; means forming with said device, a four arm capacity bridge, said electrodes being each connected respectively to a corner of the bridge; an input circuit connecting across a diagonal of the bridge; a circuit connecting across the other diagonal of the

bridge; and means whereby a capacitive reactance for the range of operation of the device is formed with said circuit that connects across the said other diagonal, said reactance being effective between the input and output electrodes.

13. In an amplifying system, an electronic emission device having input and output electrodes, means forming with the capacity between the electrodes a four armed capacity bridge, an input circuit connected across one diagonal of said bridge, and a circuit connected substantially across the other diagonal of said bridge, the said latter circuit including a pair of coupled coils, and a coil connecting between said pair of coils and an input electrode.

14. In an amplifying system, an electronic emission device having an electron emitting electrode, an anode, and a control electrode; means forming with the interelectrode capacities of said device, a four armed capacitive bridge, the electron emitting electrode and the control electrode being connected to diagonally opposite points, and the anode to one of the other points of the bridge; and a circuit connected substantially across the other diagonal, said circuit including a coil that carries the output current and said coil and one of the capacities of the bridge forming parts of a parallel resonant circuit having a frequency below the range of operation of the system.

15. In an amplifying system an electronic emission device having an electron emitting electrode, an anode, and a control electrode; means forming with the interelectrode capacities of said device, a four armed capacitive bridge, the electron emitting electrode and the control electrode being connected to diagonally opposite points, and the anode to one of the other points of the bridge; a circuit including a pair of coupled coils connected substantially across the other diagonal; and a coil connecting between the said coils and to the electron emitting electrode.

16. The combination as set forth in claim 15, in which there is included another pair of coupled coils, one in the arm of the bridge that extends between the anode and the electron emitting electrode, and the other in that arm which extends between the electron emitting electrode and that point on the bridge to which none of the three electrodes connect.

17. The combination as set forth in claim 15, in which there is included another pair of coupled coils, one in the arm of the bridge that extends between the anode and the electron emitting electrode, and the other in that arm which extends between the electron emitting electrode and that point on the bridge to which none of the three electrodes connect, the capacities and coils being so proportioned that a substantially constant reactive effect is

produced thereby between the input and the output side of the electron emitting device for its range of frequency operation.

18. In an amplifying system, an electronic emission device, an input circuit for said device, an output circuit for said device, said output circuit including a series inductance, and a parallel circuit connected to said inductance and forming therewith a circuit 10 that is resonant at a frequency below the range of operation of the system, said inductance being coupled to said input circuit.

19. In an amplifying system, an electronic emission device, an input circuit for said device, an output circuit for said device, said output circuit including an output impedance and a series inductance, and a circuit including capacity connected in parallel with said impedance and inductance and forming therewith a circuit that is resonant at a frequency below the range of operation of the system, said inductance being coupled to said input circuit.

20. In an amplifying system, an electronic emission device having an input circuit and an output circuit including an inductance, means for neutralizing capacitive coupling between the electrodes of said device comprising a coil coupled to said output inductance and a capacity connected between said coil and said input circuit, and a circuit including capacity connected in parallel with said inductance and coil and forming therewith a parallel circuit which is resonant at 30 a frequency below the range of operation of the system.

21. In an amplifying system, an electronic emission device having an input circuit and an output circuit including an inductance, 40 means for neutralizing capacitive coupling between the electrodes of said device comprising a coil coupled to said output inductance and a capacity connected between said coil and said input circuit, a pair of capacities in series connected in parallel with said inductance and coil, and a connection between the common terminal of said capacities and the common terminal of said inductance and coil whereby two parallel resonant circuits 45 are formed, each of said parallel circuits being resonant at a frequency below the range of operation of the system, and a pair of coupled inductances one in said output circuit and one in said neutralizing circuit.

22. In an amplifying system, an electronic emission device, an input circuit for said device, an output circuit for said device, means associated with at least one of said circuits to oppose the effect of capacitive coupling between the electrodes, means forming with 70 said associated means a parallel resonant circuit the resonant period of which is below the range of operation of the system, and an inductive reactance in circuit with said parallel circuit, the combined impedance of said parallel circuit and inductive reactance providing substantially uniform amplification over the operating range.

24. In an amplifying system, an electronic emission device having an input circuit and an output circuit including an inductance, 80 means for neutralizing capacitive coupling between the electrodes of said device comprising a coil coupled to said output inductance and a capacity connected between said coil and said input circuit, a circuit including capacity connected in parallel with said inductance and coil and forming therewith a parallel circuit which is resonant at a frequency below the range of operation of the 90 system, and an additional series inductance in said output circuit.

25. In an amplifying system, an electronic emission device having an input circuit and an output circuit including an inductance, a circuit for neutralizing capacitive coupling between the electrodes of said device comprising a coil coupled to said output inductance and a capacity connected between said coil and said input circuit, a pair of capacities in series connected in parallel with said inductance and coil, a connection between the common terminal of said capacities and the common terminal of said inductance and coil whereby two parallel resonant circuits 105 are formed, each of said parallel circuits being resonant at a frequency below the range of operation of the system, and a pair of coupled inductances one in said output circuit and one in said neutralizing circuit.

In testimony whereof I have hereunto set my hand.

HAROLD F. ELLIOTT.

22. In an amplifying system, an electronic emission device, an input circuit for said device including a coil, and an output circuit for said device including a coil inductively coupled to the coil in the input circuit, means whereby the effect due to this coupling upon the input circuit is that of a capacitive reactance within the range of operation of the system, and inductively reacting means in said output circuit whereby uniform amplification over the operating range is obtained.

23. In an amplifying system, an electronic emission device having a plurality of elec-
